UNITED STATES PATENT OFFICE.

HUBERT BEDDOES, OF PHILADELPHIA, PENNSYLVANIA.

APPARATUS FOR EJECTING FLUID MATTER.

1,006,822.

Specification of Letters Patent. Patented Oct. 24, 1911.

Application filed March 11, 1911. Serial No. 613,889.

To all whom it may concern:

Be it known that I, HUBERT BEDDOES, a citizen of the United States, and a resident of the city and county of Philadelphia and State of Pennsylvania, have invented an Improvement in Apparatus for Ejecting Fluid Matter, of which the following is a specification.

Heretofore it has been customary to eject sewage and other fluid matter from tanks by air acting expansively, *i. e.* at each operation, there is admitted to the tank that charge of air under pressure which acting expansively will give a resulting pressure sufficient to lift the liquid to the point of discharge.

It is the object of the present invention to accomplish the desired object by the use of less air, or of air under less pressure, and this result I accomplish by mingling with the air admitted to the tank a quantity of steam or other hot vapor or gaseous fluid under pressure. The high temperature of the steam, vapor or gas, thus mixed with the air acts to raise the temperature of the air and thus increases its expansion. The air thus mingled with the steam, vapor or gas, retards condensation and the effect produced is the result of the combined action of both the steam, vapor or gas, and air acting expansively on the liquid.

By the addition of a small quantity of steam sufficient expansion may be obtained to eject the contents of the tank from a charge of air, which, without the steam, would be wholly inadequate. When there is available for the purpose exhaust steam or hot gases exhausted from a gas engine, which would otherwise be wasted, a great saving may be effected by the use of the invention. My invention is not, however, limited to the use of exhaust steam, gases or vapors, but the steam, gas or vapor, used must have sufficient heat and pressure to raise the temperature of the air to a substantial extent.

The drawing shows a partly sectional side elevation of an apparatus embodying the invention.

a is any appliance to which the pressure is applied at intervals; as shown it is a forcing tank or receptacle which receives sewage through a supply pipe *a'*, and from which the sewage is discharged through a discharge-pipe *a''*.

d is a fluid pressure pipe which leads to

the upper part of the receptacle *a*, as through the mixing chamber *b* opening into the top *a³* of the receptacle.

d' is the pressure-main from which the pipe *d* leads, the communication between the pipe *d* and the main *d'* being controlled by the valve mechanism *c*. 60

o² is a pipe leading from an exhaust-pipe or any other source of supply, by which steam or other hot vapor or gaseous fluid above atmospheric pressure is supplied to the mixing chamber *b* and receptacle *a*. The pipe *o²* is provided with a hand valve *o³*. 65

f is a small bell in the upper part of the appliance *a* from which an air-pipe *f'* leads to the valve-mechanism *c*. 70

k is a valve in the pipe *o²* which is controlled through an air-pipe *k'* from the valve-mechanism *c*. As shown this valve is 75 opened by a small pressure-motor *k²* operated by the pressure admitted through the pipe *k'* and is closed by a spring *k³* when the pressure in the pipe *k'* is relieved.

When the sewage, or other liquid, rises in 80 the tank *a* beyond the end of the bell *f*, air is forced through the pipe *f'* to the valve-mechanism, and puts that mechanism in operation to admit air under pressure to the pipes *d* and *k'*. A small quantity of 85 steam, vapor or gas, is thus admitted to the chamber *b* and tank *a* with a charge of air. The air and steam, vapor or gas, thus admitted act expansively upon the surface of the liquid contained in the receptacle *a* and drive the liquid out through the discharge pipe *a''*. As the temperature of the air is 90 raised by the steam, vapor or gas, its expansion is increased, and at the same time the mingling of the air with the steam, vapor, or gas, retards condensation, so that 95 the expansive force is much greater than could be obtained by the action of steam or air alone; and the force required to discharge the contents of the receptacle *a* can 100 be obtained with air at less pressure, when supplemented by a small volume of steam, than would otherwise be possible. When 105 exhaust steam, vapor or gas,—which would otherwise be wasted—is used for the purpose, a substantial saving results in the operation of the apparatus.

The particular construction of the valve-mechanism which controls the admission of the air and steam is not material to the invention. Any form of mechanism may be employed which will operate to admit a 110

change of air to the pipe d and simultaneously open a valve in the pipe o^2 . For the purpose of illustration I have shown the valve-mechanism fully described in Letters Patent No. 979,698, dated December 27th, 1910. By this mechanism, at each operation a main valve is momentarily opened to admit a charge of air from the main d^4 to the air pipe d , and at the same time a charge of air is admitted through branch pipes d^3 , d^5 to the pipe k' . This acts on the motor k^2 to open the valve k for an instant and admit the desired quantity of steam.

It is to be understood that where in the claims I speak of the pipe o^2 as a "steam-pipe" I mean to include such a pipe when used to supply any other hot vapor or gaseous fluid for the purpose described.

What I claim is as follows:

1. In apparatus of the character described, the combination of a tank to contain fluid matter having a discharge-pipe, an air-pressure-pipe and a steam-pipe leading to said tank, and valve-mechanism controlling said steam-pipe and air-pipe to control the admission of steam and air together to said tank.

2. In apparatus of the character described, the combination of a tank to contain fluid matter having a discharge-pipe, an air-pressure-pipe and a steam-pipe leading to said tank, and valve-mechanism controlling said steam-pipe and air-pipe to control the admission of steam and air together to said tank and controlled by the conditions in said tank.

3. In apparatus of the character described, the combination of a tank to contain fluid matter having a discharge-pipe, an air-pressure-pipe and a steam-pipe leading to said tank, and valve-mechanism controlling said steam-pipe and air-pipe to control the

admission of steam and air together to said tank, said valve-mechanism being located wholly exterior to the tank but controlled by the conditions therein. 45

4. In apparatus of the character described, the combination of a tank to contain fluid matter having a discharge-pipe, a mixing chamber opening into the upper part of said tank, an air-pressure-pipe and a steam-pipe leading to said mixing chamber, and valve-mechanism controlling said steam-pipe and air-pipe to control the admission of steam and air together to said mixing 50 chamber. 55

5. In apparatus of the character described, the combination of a tank to contain fluid matter having a discharge-pipe, an air-pressure-pipe and a steam-pipe leading to said tank, valve-mechanism controlling said steam-pipe and air-pipe to control the admission of steam and air together to said tank, an air-bell in said tank, and an air-pipe leading from said air-bell to the valve-mechanism and controlling its operation. 60 65

6. In apparatus of the character described, the combination of a tank to contain fluid matter having a discharge-pipe, an air-pressure-pipe leading to said tank, a steam-pipe 70 also leading to said tank, a valve-device in said steam-pipe, an air-pipe leading to said valve-device in the steam-pipe and controlling it, and valve-mechanism for controlling the admission of air to said air-pipe leading to the tank and to the air-pipe leading to the valve-device in the steam-pipe. 75

In testimony of which invention, I hereunto set my hand.

HUBERT BEDDOES.
